UNITED STATES PATENT OFFICE

EUGENE H. MCGEE, OF CHICAGO, ILLINOIS, ASSIGNOR, BY MESNE ASSIGNMENTS, TO
SIGNODE STEEL STRAPPING COMPANY, A CORPORATION OF DELAWARE

SEAL

Application filed December 30, 1925. Serial No. 78,331.

My invention relates to improvements in seals, and is particularly concerned with the provision of a metallic seal for securing together overlapping portions of metallic strapping such as is used in the binding or 5 fastening of boxes, bales and other packages.

The present type of seal embodies the general characteristics of the seal disclosed in Flora Patent No. 1,252,680, but improves 10 upon the generic construction shown in this Flora patent by providing a unique overlapping relation of the flanges which embrace the under sides of the overlapping strapping.

Two prominent objects obtained by this 15 overlapping relation of the flanges are:

(1) *Increased tensile strength.*—This increased tensile strength is due to the additional layer of opposing shoulders in the crimp joint, resulting from the overlapping 20 relation of the flanges, and is also due to the increased resistance of the joint to unfolding at the point of crimping. Failure of the Flora type of seal, and seals similar thereto, 25 is usually due to the slow opening up of the crimp, this acting to decrease the resisting effect of the shoulders in the crimp. The additional layer of opposing shoulders afforded by the overlapping relation of the flanges interposes increased resistance to this unfolding or opening up of the crimp.

(2) *Smoothness of the under surface.*—One of the objections to the present type of seal, such as the Flora seal, is that the seal is apt to bulge inwardly when crimped, resulting 35 in sharp projections, this being particularly true if the metal runs a little hard. By the present relation of overlapping flanges, these bulging portions are forced back into position, leaving the under side of the seal 40 smooth and free from projections which would mar the surface of the material being strapped. This is an extremely important point in the case of fiber cartons, of bales of woven goods, of bundles of finished material, 45 of bundles of woodwork, etc., where the chafing and scoring of the inwardly projecting flanges of the present type of seal often damage a considerable amount of goods. It is also note-worthy that the elimination of the 50 bulging projections from the inner side of

the seal allows this side to rest closely to the package, thereby bringing the strap in closer juxtaposition to the package with the consequent greater security against being torn off by chance nails or other projections.

55

Referring to the accompanying drawing in which a preferred embodiment of my invention is illustrated:

Figure 1 is a perspective view, showing in 60 disassembled relation two strap ends, and the present seal by which these strap ends are joined together;

Figure 2 is a similar view showing the same parts assembled in readiness for the crimping operation;

65

Figure 3 is an edge view of the connected strap ends, showing the present form of seal in side elevation after one crimping operation has been performed thereon;

Figure 4 is a plan view taken from the bottom or inner side of the joint illustrated in Figure 3;

Figure 5 is a plan view taken from the outer or upper side of the joint, after two crimping deformations have been made in the seal;

75

Figure 6 is a transverse sectional view on a considerably larger scale, taken approximately on the plane of the line 6—6 of Fig. 5, and

Figure 7 is a transverse sectional view, 80 on the same scale, taken on the plane of the line 7—7, Fig. 5.

In binding and sealing packages in accordance with the method of sealing disclosed in the above mentioned Flora patent and 85 contemplated in the present application, a length of strapping 12 is passed around the package in the direction in which the latter is to be bound, and this strapping is then cut off to leave overlapping strap ends 12^a and 12^b. Over these overlapping strap ends is 90 then slipped a seal 13. After the strap has been drawn up tightly around the package, through the use of a suitable tensioning tool, well known in the art, the joint formed by the strap ends engaging in the sleeve 13 is 95 crimped laterally by a suitable crimping tool to provide interlocking deformations in the seal and in the strap ends. This deforming or crimping operation may be performed at 100

an intermediate point in the length of the seal, or at two spaced points indicated at 14—14 in Fig. 5, the latter practice of crimping the seal at two spaced points being preferable as it affords a stronger joint. This crimping operation forms interlocking shoulders in the several thicknesses of the strap ends and of the sealing sleeve, which shoulders securely lock the two strap ends against separation.

10 The sealing sleeve 13 of the present invention embodies a substantially rectangular back portion 13^a and flanges 13^b and 13^c, similar to the Flora seal. In the Flora seal, however, the flanges 13^b and 13^c merely overlap the strap edges 12^a and 12^b a short distance, the inner edges of these flanges having a considerable space therebetween when the sleeve is in position over the strap ends. It 15 is the unconfined edges of these relatively narrow flanges in the Flora seal which tend to bulge outwardly at certain points in the completed seal and form scarring and chafing projections.

20 25 In the present seal, one of the flanges 13^c is lapped over the other flange 13^b to a considerable depth, substantially in the proportions illustrated in Figures 1 and 2. The inner flange 13^b is preferably of a width equal 30 to substantially one-half the overall width of the seal, so that its edge 13^d terminates substantially on the median line of the seal. The edge 13^e of the outer overlapping flange 13^c preferably does not extent all the way out to 35 the outer margin of the seal, but has a considerable amount of overlap over the edge 13^d.

30 The result secured by this overlapping relation is illustrated in Figures 4, 6 and 7. 40 In the crimped area 14, the narrow inner flange 13^b will extend up to approximately the center of the joint, so that its edge 13^d will terminate approximately in the upper central part of the crimp. This insures that 45 this flange will be held against outward bowing or flexure downwardly out of the crimped deformations 14 against a very high tensile stress imposed on the joint, thereby increasing the tensile strength of the joint. 50 The relatively wide overlapping flange 13^c will overlap and confine this upper edge 13^d of the inner flange and will extend down in overlapping relation to this inner flange almost to the bottom of the crimp. As indicated in Fig. 6, the lower edge 13^e will not, however, project below the bottom of the crimped deformation where it might scar or deface the package or article. This overlapping portion 13^e thus assists in holding 60 the shorter flange 13^b against the action of being sprung out of the crimp under considerable endwise tension; and this overlapping flange 13^c also reinforces the crimp 14 by providing an additional thickness of metal 65 forming additional locking shoulders for re-

sisting to a still greater degree any tendency of the crimp deformation 14 to open up under endwise tension.

Referring now to the greater smoothness of the under surface of the seal attained by the present overlapping relation of the flanges, it seems to inherently follow from the action of the crimping jaws of the crimping tool that the metal in the intermediate portion 15 of the joint, between the points of crimping 14, is bulged inwardly or downwardly toward the package, substantially as illustrated in Fig. 7. This is also true to some extent at the end portions 16—16 of the seal, particularly where such end portions project a fair distance beyond the points of crimping 14—14. This downward curvature or convexity of the seal at these intermediate and end portions will spring or bow downwardly the flange edges which are free to be sprung outwardly under the stress of this slight curvature. It will be evident that in the case of the Flora seal this curvature will present the two lower edges of the relatively short flanges at an angle to the surface of the package where they can scrape and scar the surface. In the case of the present construction, however, it is obvious that the inner flange 13^b is almost entirely covered so that there is no possibility of the edge 13^d of this inner flange ever contacting with the surface of the package. Also, because of the considerable width of the outer overlapping flange 13^c the edge 13^e of this flange terminates at a point where the flange has a slight upward or outward curvature so that this edge is not turned downwardly at an angle where it could scar or deface the surface of the package.

Having thus described my invention, what I claim is:

1. A tension resisting joint for package strapping comprising in combination the portions of the strapping to be joined, and a sealing sleeve embracing said strapping and comprising two flanges, in which crimped deformations are made, one of said flanges overlapping the other and the outermost of said overlapping flanges having its edge lying well beyond the median line of the sleeve.

2. A tension resisting joint for package strapping comprising in combination the portions of the strapping to be joined, and a reinforcing sleeve comprising a back portion and overlapping flanges extending from the longitudinal edges thereof, said reinforcing sleeve and said strap ends having conjoint interlocking marginal deformations, the innermost of said flanges extending substantially to the center of said marginal deformations and the outermost flange extending well beyond the median line of the sleeve to a point substantially adjacent one longitudinal edge of the sleeve.

3. A tension resisting joint for package strapping comprising in combination the portions of the strapping to be joined; and a re-enforcing member embracing said strapping comprising a back portion and flanges projecting from the longitudinal edges thereof, the re-enforcing member and said strapping having interlocking tension resisting deformations formed therein, the portion of 10 said re-enforcing member spaced longitudinally from said tension resisting deformations having a convex curvature toward the surface of the box or package, one of the flanges of said re-enforcing member 15 extending beyond the median line of said re-enforcing member whereby its edge is curved away from the box or package in the convexly curved portion of said re-enforcing member.
2. 4. A tension resisting joint for package strapping comprising in combination the portions of the strapping to be joined and a sealing sleeve embracing said strapping and having two overlapping flanges, in which 25 sidewise crimped deformations are made, the portion of said sleeve spaced longitudinally from said sidewise crimped deformations having a convex curvature toward the surface of the package, the outermost of said 30 flanges having its edge at one side of the mid-point of said convex curvature.

In witness whereof, I hereunto subscribe my name this 24th day of November, 1925.

EUGENE H. McGEE.
